STUDIO LOUNGE

Filed Dec. 15, 1933

5 FIG. 1

UNITED STATES PATENT OFFICE

2,058,337

STUDIO LOUNGE

Ulysses Bruce McMurtry, Toronto,
Ontario, Canada

Application December 15, 1933, Serial No. 702,640

5 Claims. (Cl. 5—44)

The present invention covers improvements and additions to an invention on studio lounges, filed September 27th, 1933, Serial Number 691,201 by the same inventor, Ulysses Bruce McMurtry, and relates more particularly to a collapsible "back" member for a modified form of the invention. A guiding means is also provided herein for placing the lower bed member in position beneath the upper bed member and is illustrated in Figures 10 2 to 4 inclusive of the present specification.

The form of "back" member used in connection with the present invention is illustrated in Figures 1 to 3 inclusive of the drawing.

In the accompanying drawing forming part of the present specification, the figures and numerals used are in consecutive order and proper sequence with those of the above mentioned United States application, and in which:

Figure 1 is a plan view of a portion of the upper bed of a modified form of my invention, having a collapsible back mounted thereon.

Figure 2 is a transverse section on line 2—2 of Figure 1.

Figure 3 is a rear elevation of Figure 2 illustrating the features of the collapsible back used in this form of the invention.

Figure 4 is a plan view of the removable bed used in connection with this modified form of the invention.

Figure 5 is a transverse section on line 5—5 of Figure 1.

With reference to the form of the device in hand, shown in Figures 1 to 4 inclusive, 87 indicates a back member, composed of a pair of opposed vertical bars 88, 88 rigidly mounted on a channel shaped member 89 which is hinged at 90 to depending plates 131, 131, which are rigidly mounted on the longitudinal stringer 91 of the upper bed member 92. Between the opposed vertical bars 88, 88 are the flat straps 93, 93 etc., which are yieldingly attached by means of the springs 94, 94 etc., to said vertical bars. The outer ends of the vertical bars 88, 88 are joined by a preferably tubular member 130, as shown in Figure 3. The back member 87 is held in position by means of the following parts, to wit: a pair of bars 95, 95 adjacent to each of the bed ends 96, 96 which are pivotally connected at 97 to the transverse member 121 and slidably attached at 98 to the back member 87, by means of a small angle 99. It will be noted that a slot 100 is formed in the bar 95 to permit the pin 101 to slidably operate therein when the back is lowered on the top of the bed. A pair of bars 102, 103 at each end of the bed adjacent to the bed

ends 96, 96 and which are pivotally connected to each other at 104 are used to hold the back 87 in rigid position. The bar 102 is pivotally connected at 105 to a vertical stop angle 106, the latter being mounted on the longitudinal stringer 91 and also attached to the bed end 96 as clearly illustrated in Figure 2.

A bar 103 is pivotally connected with the channel 89 at 107. When the back member 87 is thrown forward over the upper bed member 92, as indicated in the dotted line at 108, it is seen that the bars 102 and 103 collapse as shown dotted at 109, while the back member 87 takes the position 110. The bar 95 is swung forward about the pivot point 97 and takes the position 111. From which it is seen that the back member 87 may be lowered completely on top of the upper bed member 92, the depth of the channel 89 being sufficient to embrace the upper bed member 92 when the cushion 113 is removed therefrom.

The lower bed member 114 is provided with a front piece 119, which extends the full width between the bed ends 96, 96 and it is seen that the space 116 may be used for the storage of bedding.

The cushion 117 is normally lodged in the channel 89 and rests against the back member 87, and the lounge may be furnished with additional small cushions 118, which rest against the cushion 117 and said back member 87. This cushion 117 when the lower bed member 114 is withdrawn from the lounge, is placed on top of said member 114 as is at once understood and the back 87 is thrown down upon the upper bed member 92 and the cushion 113 is placed on top of same completely hiding the back from view.

It will be seen from Figs. 2 and 4 that the lower bed member is furnished with universal castors 112, 112 for ready manipulation and movement of the lower bed member 114 within the bed ends 96, 96.

The lower bed member 114 is also supplied with rollers 115 and 120, as shown in Figures 2 and 4, adapted to engage the inner face of the bed ends 96, 96 and the rollers 115, 115 are also adapted to engage against the stop angle 106 before mentioned.

The operation of the modified form thus described is believed quite obvious from what has been said above. The bed member 92 normally has a cushion 113 thereon and the back member 87 normally supports the cushion 117 and the smaller cushions 118, thereby forming a desirable and attractive type of studio lounge. Bedding may be stored in the space 116.

When it is desired to form double beds, the lower bed member 114 is withdrawn from between the bed ends 96, 96, the cushion 113 is lifted and the back 87 thrown forward on top of 5 the bed member 92 and the cushion 113 placed thereupon. The cushion 117 is placed on the lower bed member 114.

Thus two beds are provided, which may be used separately or placed in juxtaposition to each 10 other.

I claim:

1. In a studio lounge, a lounge frame, having a pair of opposed bed ends thereon, a back for the lounge adapted to operate between said bed 15 ends, comprising a channel hingedly mounted on the rear of the lounge frame, a substantial distance below the top thereof, and having sufficient transverse width when the back is placed in a horizontal position to embrace the top of the 20 frame, a pair of opposed vertical bars, rigidly mounted on the channel, a longitudinal strut rigidly connected to the upper ends of said bars, a plurality of horizontally disposed strap members each of which is yieldingly attached to the 25 opposed vertical bars, and foldable means for holding the back in a vertical position, and connecting the said back with the lounge frame, adapted to permit revolution of the back into a horizontal position upon the frame.
2. In a studio lounge having a cushion, a lounge frame, a pair of opposed bed ends therefor, a back for the lounge adapted to operate between said bed ends comprising a channel hingedly mounted on the rear of the lounge 30 35 frame, a substantial distance below the top thereof, and having sufficient transverse width when the back is placed in a horizontal position to embrace the top of the frame, a pair of opposed vertical bars, rigidly mounted on the channel, a longitudinal strut rigidly connected to the upper ends of said bars, and foldable means for holding the back in a vertical 40 45 position, and connecting the said back with the lounge frame, adapted to permit revolution of the back into a horizontal position upon the frame.
3. In a studio lounge having a cushion, a lounge frame, a pair of opposed bed ends therefor, a back for the lounge adapted to operate between said bed ends comprising a channel hingedly mounted on the rear of the lounge frame, a substantial distance below the top thereof, and having sufficient transverse width when the back 50 55 is placed in a horizontal position to embrace the top of the frame, a pair of opposed vertical bars,

rigidly mounted on the channel, a longitudinal strut rigidly connected to the upper ends of said bars, a plurality of horizontally disposed strap-members each attached to the opposed vertical bars and foldable means for holding the back in 5 a vertical position comprising a slotted bar on each end of the lounge, pivotally connected to the lounge frame and means connecting each slotted bar with one of the opposed vertical bars, a pair 10 of supporting bars at each end of the lounge, pivotally connected to each other, to the lounge frame and the channel, both the slotted bars and the pivotally connected supporting bars being adapted to permit the revolution of the back of the lounge into a horizontal position over the 15 frame of the lounge and be completely hidden by the lounge cushion when same is superimposed upon said back.

4. In a studio lounge, a lounge frame having a pair of opposed bed ends thereon, a back for the 20 lounge adapted to operate between said bed ends, comprising a channel hingedly mounted on the rear of the lounge frame, a substantial distance below the top thereof, and having sufficient 25 transverse width when the back is placed in a horizontal position to embrace the top of the frame, a pair of opposed vertical bars, rigidly mounted on the channel, a longitudinal strut rigidly connected to the upper ends of said bars, and foldable means for holding the back in a vertical 30 35 position, and connecting the said back with the lounge frame, adapted to permit revolution of the back into a horizontal position upon the frame.

5. In a studio lounge having a cushion, a lounge 35 frame, a pair of opposed bed ends therefor, a back for the lounge adapted to operate between said bed ends comprising a channel hingedly mounted on the rear of the lounge frame, a substantial distance below the top thereof, and having sufficient transverse width when the back is placed in a horizontal position to embrace the top of the frame, a pair of opposed vertical bars, rigidly mounted on the channel, a longitudinal 40 45 strut rigidly connected to the upper ends of said bars, and foldable means for holding the back in a vertical position comprising a slotted bar on each end of the lounge, pivotally connected to the lounge frame and means connecting each slotted bar with one of the opposed vertical bars, a pair 50 55 of supporting bars at each end of the lounge, pivotally connected to each other, to the lounge frame and the channel, both the slotted bars and the pivotally connected supporting bars being adapted to permit the revolution of the back of the lounge into a horizontal position over the frame of the lounge and be completely hidden by the lounge cushion when same is superimposed upon said back.

ULYSSES BRUCE McMURTRY.
